Primary Examiner — Mark Goodwin

(57) **CLAIM**

The ornamental design for the doorframe bracket, as shown and described.

DESCRIPTION

FIG. 1 is a top perspective view of a doorframe bracket showing my new design;

FIG. 2. Is a top view thereof;

FIG. 3. Is a backside view thereof;

FIG. 4 is a front view thereof;

FIG. 5. Is a lateral side view thereof; and,

FIG. 6. Is a perspective view of a doorframe with the brackets attached.

The broken lines disclose unclaimed environmental subject matter of the design in use.
